Primary Examiner — John R Yeh*Assistant Examiner* — Dustin Andrew Griffith(74) *Attorney, Agent, or Firm* — Hawaii Patent Services; Nathaniel K. Fedde; Kenton N. Fedde(57) **CLAIM**

The ornamental design for a home emergency backpack, as shown and described.

DESCRIPTION

FIG. 1 is a perspective view of my new design, showing a home emergency backpack;

FIG. 2 is another perspective view thereof;

FIG. 3 is another perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged partial view of a part enclosed 10 in FIG. 1.

The line shading in FIGS. 1–10 represents contour and not surface ornamentation.

The broken lines shown in the FIGS. 1–10 illustrate portions that form no part of the claimed design.

1 Claim, 10 Drawing Sheets(56)
